UNITED STATES PATENT OFFICE

123,893

DESIGN FOR A GAS RANGE

Elmer D. Pellegrin, Woodstock, Ill., assignor to
Geo. D. Roper Corporation, Rockford, Ill., a cor-
poration of Illinois

Application January 29, 1940, Serial No. 89,856

Term of patent 7 years

To all whom it may concern:

Be it known that I, Elmer D. Pellegrin, a citizen of the United States, residing at Woodstock, in the county of McHenry and State of Illinois, have invented a new, original, and ornamental Design for a Gas Range, of which the following is a specification, reference being had to the accompanying drawing, forming part thereof.

In the drawing:

Fig. 1 is a perspective view of a gas range embodying my new design;

Fig. 2 is an enlarged front elevational view of the flue deflector shown in full lines in Fig. 1;

Fig. 3 is a horizontal sectional view thereof on the line 3—3 of Fig. 2;

Fig. 4 is a top plan view thereof, and

Fig. 5 is an end elevational view thereof.

The dominant features of the design are those shown in full lines.

I claim:

The ornamental design for a gas range, substantially as shown and described.

ELMER D. PELLEGRIN.
